UNITED STATES PATENT OFFICE.

NICHOLAS S. VEDDER AND FRANCIS RITCHIE, OF TROY, AND TOBIAS S. HEISTER, OF LANSINGBURG, ASSIGNEES TO NICHOLAS S. VEDDER, OF TROY, NEW YORK.

DESIGN FOR BASE-BURNING STOVE.

Specification forming part of Design No. 8,006, dated January 12, 1875; application filed December 30, 1874.
[Term of Patent 3½ years.]

To all whom it may concern:

Be it known that we, NICHOLAS S. VEDDER, of the city of Troy, in the county of Rensselaer and State of New York, FRANCIS RITCHIE, of said city of Troy, and TOBIAS S. HEISTER, of the village of Lansingburg, in said county of Rensselaer, New York, have jointly invented and produced a new and original Design for Base-Burning Stoves, of which the following is a specification, reference being had to the accompanying cut, print, or engraving of a stove having our said new design.

One part of this invention consists of the design for the urn A, composed of the globular body B, having the equatorial band c, ornamented by the interrupted angular bead d, and also having the semicircular places e between the equatorial ends of the sectional panels f, with the depressed trifid ornaments g therein, and the said globular body having lateral studs h, with pendent handles i, and the cap-piece j and base-stem k, all shaped, ornamented, and combined substantially as represented in the aforesaid cut.

Another part consists of the design for the compound depressed ornament L in the inner panels M of the upper section, composed of the base-cup n, supporting the stem o, having lateral pairs of flower-bearing branches p, scroll-branches p¹, and leaf-branches p², and the trifid top q, all shaped, ornamented, and combined as represented in the aforesaid print.

Another part consists of the design for the panels of the upper section, composed of the central depressed ornament L in the inner panel M, the depressed border ornamentation r, the rectangular transversely ribbed or grooved border-molding s, having ornamented square corner-pieces s', and the surrounding rectangular surface t, ornamented by the series of connected radial impression ornaments, all shaped and arranged together so as to appear substantially as represented in the aforesaid engraving.

Another part consists of the design for the doors U, each having three illuminating-windows therein, with transversely ribbed or

grooved intervening stiles v v and caps w, each formed by a central horizontal and two lateral inclined moldings, and all surrounded by a border-molding x, having an outwardly-turned scalloped edge, and the whole surmounted by the cap-piece y, formed by the horizontal and two lateral inclined moldings above the space z over the middle window, and horizontal moldings terminating in scrolls over and upon the horizontal parts of the tops of the two outer windows, all shaped, ornamented, and combined as represented in the aforesaid print.

Another part consists of the design for the doors C, each having therein two illuminating-windows, with the stile a between them, and with caps b, each formed by a horizontal central and two lateral inclined moldings, and all surrounded by a border molding, l, having a scalloped edge turned outward, and the whole surmounted by a cap-piece, m, formed by the central horizontal and two short lateral inclined moldings above the angular space u, over and between the inner upper parts of the cap-moldings of the two windows, and horizontal moldings terminating in scrolls over and at the outer ends of the horizontal parts of the said moldings immediately over the two windows, the whole being shaped, ornamented, and combined as represented in the aforesaid engraving.

Another part consists of the design for the top plate D of the lower base-section, composed of the outer compound molding E, surrounding the flat ornamented portion F, and the concave or inclined part G, having thereon the series of ornaments H, arranged side by side, with the lower parts ovate-acuminate and pointed downward, and with acuminate-ovate ornamentations thereon, and with the upper parts narrower than the lower parts, and having straight sides and contracted ends, with upwardly-pointed long and narrow ornamentations with rounded lower ends on the wider portions of the upper parts, and the whole shaped, ornamented, and arranged substantially as represented in the aforesaid cut.

Another part consists of the design for the side panel I of the lower section, composed of the inner and outer sunken ornaments J and K in the plain, curved, rectangular inner panel N, the transversely ribbed or grooved surrounding border-molding P, with square ornaments on its corners, and the outer surrounding ornamental surface Q, all shaped, ornamented, and arranged together as represented in the aforesaid engraving.

We do not herein claim the zigzag folded fillet ornamentation R.

What we claim as our joint invention is—

1. The design for the urn A, composed of the globular body B, equatorial band c, with ornaments d, parts e and f, with ornaments g, lateral studs h, with pendent handles i, cap-piece j, and base-stem k, all shaped, ornamented, and combined as shown and described.

2. The design for the compound depressed ornament L in the inner panel M of the upper section, composed of the vase n, stem o, leaf, scroll, and flower branches p p¹ p², and top q, all shaped and arranged as specified and shown.

3. The design for the panels or divisions of the upper section, composed of the depressed central compound ornament L and surrounding ornamentation r in the inner panel M, the border-molding s, with corner ornaments s', and the surrounding ornamental surface t, all shaped, ornamented, and arranged together as shown and specified.

4. The design for the doors U, composed of the three illuminating-windows with the stiles v v, caps w, molding x, cap-piece y, and space or recessed surface z, all shaped, ornamented, and arranged together as described and shown.

5. The design for the doors C, composed of the two illuminating-windows with the stile a, caps b, border-molding l, cap-piece m, and angular recess u, all shaped, ornamented, and disposed together as specified and shown.

6. The design for the lower top plate D, composed of the compound molding E, flat surface F, and inclined portion G, with the ornaments H thereon, all shaped, formed, ornamented, and arranged together as shown and described.

7. The design for the side panel I of the lower base-section, composed of the inner and outer sunken ornaments J and K in the panel N, border-molding P, and ornamental surface Q, all shaped, ornamented, and arranged together as specified and shown.

In testimony whereof we hereunto subscribe our names this 24th day of December, 1874.

NICHOLAS S. VEDDER.
FRANCIS RITCHIE.
TOBIAS S. HEISTER.
